DOOR HOLDER UNIT

Henry Knox Bryson, Vienna, Va., and Alfred B. Castle, Brookmont, Md., assignors, by direct and mesne assignments, of one-third to Milford A. Juten, Brookmont, Md., and two-thirds to said Henry Knox Bryson

Filed June 7, 1955, Ser. No. 36,396

Term of patent 14 years

(Cl. D10—7)

FIG. 1

Figure 1 is a perspective view of a door holder unit with the parts in engaged position, showing our new design.

We claim:

The ornamental design for a door holder unit, as shown.
